ROTARY CYLINDER LOCK

Edmond Uher, Paris, France

Application June 15, 1948, Serial No. 33,202
In France January 12, 1948

5 Claims. (Cl. 70—364)

1

The present invention relates to locks of the rotary cylinder type having a plurality of tumbler elements normally positioned to lock the cylinder against rotation in its casing.

The rotary cylinder locks generally comprise a cylindrical casing in which rotates the cylinder carrying transversely guided tumbler elements adapted to engage in a slot or groove provided in the casing. The fact that two functions are then assigned to the inner cylinder, viz. that of guiding the tumbler elements both in rotation and transversely excludes the possibility of manufacturing said cylinder without machining, that is to say without milling or turning, thus giving rise to a high cost of manufacture.

The principal object of this invention is to provide a lock of the rotary cylinder type which may be manufactured without machining.

Another object of the invention is to provide locks of the said type which permit of a great number of possible combinations through a substantial increase of the number of tumbler elements without correspondingly increasing the length of the cylinder.

According to the invention, the functions which were heretofore assigned to the inner cylinder alone are distributed between two different members, one adapted to guide the tumbler elements in rotation and the other to guide said elements transversely. To this effect, the inner cylinder is hollowed and provided with longitudinal slots the width of which is substantially that of the tumbler elements, a special supporting member being provided inside said cylinder for transversely guiding the tumbler elements.

This and other novel features of the invention are hereafter described in detail and shown in the appended drawings, in which:

Fig. 1 is a longitudinal sectional view of a cylinder lock;

Fig. 2 is a transverse sectional view of the same lock;

Fig. 3 is a longitudinal sectional view of the lock with the key engaged therein;

Fig. 4 is a corresponding transverse sectional view;

Fig. 5 is a transverse sectional view of the inner cylinder;

Fig. 6 is a perspective view of the guiding cage for the tumbler elements;

Fig. 7 shows three types of tumbler elements;

Fig. 8 is a perspective view of the rotary cylinder of the lock;

Fig. 9 is a similar view of a lock casing, with two longitudinal grooves;

2

Fig. 10 is a side view of the key adapted to work with said lock;

Fig. 11 is a perspective view of a lock casing with four longitudinal grooves;

Fig. 12 is a similar view of a stamped and rolled casing;

Fig. 13 is a side view of the casing;

Fig. 14 is a section through the end of the inner cylinder;

Fig. 15 is a transverse sectional view of a key provided with two longitudinally extending cam surfaces on each edge and adapted to cooperate with a lock according to the invention;

Fig. 16 is an elevational side view of said key;

Fig. 17 shows three types of tumbler elements adapted to cooperate with said key, each arranged in two different positions;

Fig. 18 shows two such tumbler elements with the key engaged therein;

Fig. 19 is a longitudinal sectional view of the lock cylinder with the key engaged therein;

Fig. 20 is a transverse section of the lock cylinder through XX—XX of Fig. 19;

Fig. 21 is a similar section through XXI—XXI of Fig. 19.

In order to increase the number of possible combinations, keys must be used which have different cross sections, which entails rotary lock cylinders arranged so that only the corresponding keys may be introduced therein. The opening provided in the inner lock cylinder and corresponding to the cross section of the key may be obtained while moulding the said cylinder, for instance by an injection moulding process, or the cylinder may be died with the necessary profiled slot. Such methods of manufacture entail a costly and complicated equipment and it is practically impossible to provide for a sufficient number of different cross sections for the keys. The known solution consisting in providing, at each end of the cylinder, guiding plates provided with profiled slots cannot be applied in practice because, particularly when the lock comprises a great number of tumbler elements, the end of the key is not guided when the latter is introduced inside the cylinder, a number of tentatives then being necessary to introduce the end of the key in the slot provided in the terminal guiding plate.

In order to secure the introduction of the key without difficulty in the whole length of the cylinder, taking into account the fact that the tumbler elements must be transversely displaced on a given length during this introduction, I propose to give the inner cylinder 1, as shown, the shape of a hollow cylindrical envelope and to

50

55

insert, in the hollow of said cylinder, between adjacent tumbler elements, a fixed guiding plate 3 attached to the cylinder, each guiding plate being provided with a slot 8 accommodating the various cross sections of the key. The said guiding plates may be stamped in a metal sheet with various shapes of slots and be formed at will to correspond to the cross sections of the keys used in combination with the cylinder.

In order to manufacture rationally the whole of the cylinder without machining, I propose to stamp first of all a flat plate intended to form the walls of the cylinder, said plate being provided, through the stamping, with all the necessary openings, then to roll up said plate to form the cylinder. In order to allow of still more easy variations of the cross section of the keys, the tumbler elements are located inside a cage which is independent of the cylinder and comprises the guiding plates for said elements.

The cylinder 1 (Figs. 1 and 4) is provided with two longitudinal slots for the insertion of the guiding cage and of the tumbler elements. At the fore end of the cylinder is secured a circular stamped closing plate 2. As above mentioned, a cage (Figs. 5 and 6) is provided to hold and guide the tumbler elements. Said cage comprises guiding plates 3 and two lateral plates 9 joining the latter and holding them together. The guiding plates 3 have lateral extensions 11 engaging in corresponding slots stamped in the lateral plates 9, which holds them apart at the right distance, the whole assembly thus forming a rigid cage. The said cage, the cross section of which corresponds to the boring of the inner cylinder 1 is freely introduced in the latter. The outer extremities of the guiding plates are extended so that they penetrate the longitudinal slots of the cylinder 1, which prevents said cage from rotating with respect to cylinder 1. A profiled slot 8 corresponding to the cross section of the key is stamped in the covering plate 2 as well as in each guiding plate, so that the key is exactly guided on its whole length. The tumbler elements 4 are set freely in the intervals between the guiding plates. These elements are all provided with a stamped rectangular slot the width of which corresponds to the thickness of the key and the height of which corresponds to the active width of the latter. The position of said slots with respect to the extremities of the tumbler elements is different according to the considered elements and there are as many such positions as there are different heights of the active portions on the corresponding key.

In the example shown at Fig. 7, three locking positions have been considered; in one case, the slot is located in the middle of a tumbler element and, in the two others, it is deported on the same distance, either upwards or downwards, the same punch being used for these two cases.

The web of key 7 has its two longitudinal edges serrated (Fig. 10) with conjugated outlines each constituted by a series of active portions 14 so disposed that their transverse axes are equidistant along said web longitudinal axis, the height of the web, measured along said transverse axes being constant while the height of said active portions 14 with respect to said web longitudinal axis, as explained above, varies according to the position of the slots in the tumbler elements with which they are intended to co-operate. Said active portions are interconnected by intermediate portions which may be either parallel to the web longitudinal axis or inclined,

e. g. by 30 or 45° thereto, according as whether they interconnect two active portions having the same height or two different heights. The key penetrates the different tumbler elements which are forcibly caused to slide transversely in both directions by said intermediate portions of the active outlines of the key. When the key is fully introduced, the tumbler elements are all set in the same position, inside the cylinder (Figs. 3 and 4) and it is then possible to rotate the cylinder 1 freely in its casing 5. When taking out the key, all the tumbler elements are pushed in the same direction by the end active portion of the key or fall downwards through their own weight, the cylinder being thus locked inside its casing 5 which is provided with two longitudinal grooves into which engage the tumbler when they are not held by the key.

The casing 5 may comprise two or four longitudinal grooves 6 the width of which corresponds to that of the tumbler elements. It may also be stamped in the shape of a flat plate comprising all the necessary openings then rolled up. In order to avoid the tumbler elements from falling out of the casing any suitable securing means may be provided, a stamped and rolled tube may be threaded on the said casing, or the latter may be inserted inside a boring provided in the body of the lock.

In order to limit the rotation of the inner cylinder 1 to an angle of 180° or 90° according to the case, the upper part 12 of the first guiding plate may be extended (Fig. 8) outside said cylinder through the corresponding longitudinal slot of the latter. The forward end of the casing (Figs. 9 and 11) is notched or cut at 13 so that extension 12 of the forward guiding plate may rotate of the desired angle in the notch thus formed.

Thanks to the small bulk of the cage and tumbler elements, it is possible to use in normal locks a cylinder having up to ten tumbler elements. If three different active positions are provided for the latter, $3^{10} = 59,049$ combinations may be obtained. If ten different cross sections of keys are used, the figure raises to 590,490. Furthermore, if two guiding plates are set one against the other in one point of the cylinder, there results a different configuration of the cam profile of the key, hence a new series of combinations. Such double guiding plates may be set in eight different positions inside the cage, thus giving $590,490 \times 8 = 4,723,920$ different combinations or different shapes of keys.

In order to obtain practically such a great number of combinations, the shape of the slots of the guiding plates and tumbler elements in the lock cylinder must be capable of being modified at will when the lock is manufactured. When using the methods of moulding or stretching usually applied hitherto for the manufacture of such locks, this is impossible to realise in practice. However, this problem is entirely solved by the present invention due to the fact that in the lock cylinder formed of separately stamped parts, the assembly of said parts and their shape may be modified at will.

In the example shown in Figs. 15 to 21, the key is formed of two separate key webs 21 and 22, that is to say two key webs having different cam surfaces, assembled for instance through soldering points. The key thus has two adjacent cam surfaces 23 and 24 on each edge.

Three different heights have here been provided for the active portions with respect to the

longitudinal axis of the web and said active portions are such that the active height i. e. the height of each web measured along the transverse axes of said active portions is constant.

The tumbler elements 25—30 (Fig. 17) are provided with slots 31 formed of two adjacent openings one of which is as long as the total height x of the webs of the key and the other has a length equal to the active height y of the webs. In the first mentioned openings, the key may pass freely without raising or lowering the corresponding tumbler element (Fig. 4); said openings are thus inactive. On the contrary, the other openings having a length y are active, the tumbler elements being brought to the desired position under the action of the active outlines of the webs on which apply the walls 32 and 33 of said other openings.

Since the active portions of the key have, in the example shown, three different heights, the distance z between the active sides 32 and 33 of slots 31 and the corresponding outer edge of the tumbler elements may have three different values. In element 25, the active part of the slot corresponding to active portions of middle height, is in the middle of the element, the distance z being the same above and under the slot.

The position of the slot is the same in element 26, but the whole of the slot is arranged symmetrically with respect to that of element 25, elements such as 26 being actuated by the surfaces 23 of the key. In the case of element 27, the active part of the slot, corresponding to higher active portions, is displaced downwards; such elements are controlled by the surfaces 24 of the key; the same elements, used symmetrically, form elements 28 which are controlled by surfaces 23 of the key.

The elements 29 are the same as elements 27 after turning the latter around their transverse axis, and elements 30 are symmetrical with respect to elements 29, the first being controlled by surfaces 23 and the second by surfaces 24 of the key. Thus, two shapes of tumbler elements give six different positions of the slots.

Two tumbler elements are placed between two successive guiding plates 3 of the cage in the lock cylinder, said elements being chosen so that one is controlled by the cam surfaces 23 and the other by the cam surfaces 24 of the key.

As two cam surfaces act upon separate tumbler elements, it is possible, with such an arrangement, to provide, with the same length of key for at least twice as many tumbler elements as in the first example shown, the safety being thus much higher than in ordinary locks.

According to the invention, it is also possible to assemble more than two cam surfaces, the slots in the tumbler elements then being formed of three adjacent openings, two of which have height x and the third height y the latter being positioned according to the cam surface and to the height of the active portion with which it is intended to cooperate.

What I claim is:

1. In a key-operated rotary cylinder lock, a fixed outer portion having wall means defining a cylindrical opening, said wall means being formed with a longitudinal recess, a rotary cylindrical member received in said cylindrical opening, said rotary cylindrical member having an internal cavity with at least one opening communicating radially with the wall means of said outer portion, a cage assembly received in the cavity of said rotary cylindrical member, said

cage assembly comprising a plurality of intermediate guide members spaced apart along the axis of the cage assembly and anchoring means for holding said intermediate guide members in fixed spaced-apart relationship to afford a rigid cage assembly, tumbler members received between spaced-apart intermediate guide members and movable radially with respect to the axis of the rotary cylindrical member to pass through the opening in the rotary cylindrical member to enter releasably the recess in the wall means of said fixed outer portion, whereby said fixed spacing of the intermediate guide members affords clearance for free radial movement of said tumblers and whereby lateral forces on said intermediate guide members along the axis of the cylindrical member are carried by said cage assembly independently of said tumbler members, and means for securing said cage assembly to said cylindrical portion to rotate therewith, whereby insertion of a key in the lock releases the tumblers from the recess to free the cylindrical member and cage assembly for rotary movement within the fixed outer portion.

2. In a rotary cylinder lock, a fixed outer portion having wall means defining a cylindrical opening, said wall means being formed with a recess, a rotary cylindrical member received in said cylindrical opening, said rotary cylindrical member having an elongated internal cavity communicating with the wall means of said outer portion through a radial opening, an elongated cage assembly received in the cavity of said rotary cylindrical member, said cage assembly comprising elongated distance piece means, a plurality of intermediate guide members anchored in said distance piece means for holding said intermediate guide members in fixed spaced apart relationship along the axis of the cage assembly to afford fixed radial channels therebetween, tumbler members received in the radial channels between spaced-apart intermediate guide members and constrained thereby to move radially with respect to the axis of the rotary cylindrical member to pass through the opening in the rotary cylindrical member to enter releasably the recess in the wall means of said fixed outer portion, whereby said fixed spacing of the intermediate guide members affords clearance for free radial movement of said tumblers and whereby forces on said intermediate guide members along the axis of the cage assembly are carried by said cage assembly independently of said tumbler members, and means for securing said cage assembly within the rotary cylindrical portion to rotate therewith.

3. In a rotary cylinder lock, a fixed outer portion having wall means defining a cylindrical opening, said wall means being formed with a longitudinal recess, a rotary cylindrical member received in said cylindrical opening, said rotary cylindrical member comprising a tubular portion having a pair of diametrically opposed, longitudinal slots, said slots placing the inner area of the tubular member in communication with the wall means of the outer portion, a cage assembly received in said tubular portion, said cage assembly comprising a pair of laterally spaced elongated distance pieces, each formed with a series of slots along its length, a plurality of slotted, spaced-apart intermediate guide plates having flat laterally extending portions received in the slots of said distance pieces to form a rigid, self-supporting cage assembly, and a plurality of randomly slotted tumbler mem-

bers received between spaced-apart intermediate guide plates and freely movable therein radially with respect to the axis of the tubular portion, said tumbler members having locking portions adapted to pass through the slots in the tubular portion to enter the recess in the wall means of the outer portion, whereby the fixed spacing of the intermediate guide plates affords clearance for free radial movement of said tumblers and whereby lateral forces on the guide plates along the axis of the cage assembly are carried by the distance pieces independently of said tumbler members.

4. A rotary cylinder lock comprising in combination with a fixed outer cylinder and slotted tumbler elements radially engageable in at least one groove provided in said outer cylinder, a rotatable inner cylinder constituted by a tubular element provided with two diametrically opposed longitudinal slots to impart rotary movement to said tumbler elements whilst permitting radial displacement thereof, a plurality of cross-shaped intermediate plates, two longitudinally extending distance pieces provided with regularly spaced transverse slots, and a lock head end plate fixed on the outer end of said tubular element, said cross-shaped intermediate plates being assembled by means of said distance pieces so as to form a rigid cage adapted to be mounted within said tubular element in such a manner that two opposed ends of each cross-shaped plate

5
10

engage said two longitudinal slots of the tubular element whilst the longitudinal edges of said distance pieces are in contact with the inner wall of said tubular element, said cage being securely held within said tubular element by said lock head end plate, and said tumbler elements being disposed between said intermediate plates so as to be guided thereby in a plane perpendicular to the longitudinal axis of said inner cylinder.

5. A rotary cylinder lock according to claim 1, wherein at least two tumbler elements are slidably positioned between each pair of adjacent, fixed intermediate guide members.
